SURF BOARD FIN AND SUPPORT BOX COMBINATION

Sigmund Kwiatkowski, Seaton, South Australia, Australia,
assignor to John Arnold's Surf Shop Pty. Ltd., Adelaide, South Australia, Australia

Filed Oct. 29, 1969, Ser. No. 19,827

Term of patent 14 years

Int. Cl. D21—03

U.S. Cl. D71—1

FIG. 3

FIG. 1 is a perspective view from one side of the surf board fin and support box combination showing my new design,

FIG. 2 is a perspective view from the other side, and
FIG. 3 is a view in plan.

I claim:

The ornamental design for a surf board fin and support box combination, as shown.
